COIN-CONTROLLED DICE MACHINE

Blanchard D. Smith, New Orleans, La., assignor,
by mesne assignments, to Mills Novelty Com-
pany, Chicago, Ill., a corporation of Illinois

Application April 13, 1932, Serial No. 605,024

20 Claims. (Cl. 273—142)

My invention relates to coin operated apparatus such as vending machines and the like and more particularly to such machines as employ novel mechanical features to stimulate trade and interest in the article vended. If often happens that coupons or cheap advertising novelties are given away as trade stimulus such as a small package of matches with the purchase of cigarettes and my machine is particularly adapted 5 for such use with the added interest of an element of chance entering into the securing of such advertising novelties as may be used to promote sales.

It also relates to games such as parchesi in 15 which an element of chance enters into the progress of each contestant and is especially adapted for such games as would require the indication and registration of the result of the throw of the dice (where dice are used as the elements of chance) for future reference or action. The device may also be used for the playing of simulated baseball or like games, the different plays being indicated by the numbers on the dice presented to view upon successive operations of the 20 machine.

Heretofore various devices have been used in the prior art to mechanically throw dice out upon a table upon the insertion of a coin or otherwise but the result of the throw in no way affected the 25 present or future mechanical action thereof and one of the objects of my invention is to provide a simple means for leaving the throw of the dice entirely to chance and yet allow the machine to indicate, register or otherwise act upon the result 30 of the throw either presently or upon a later throw.

Another object of my invention is to provide a machine in which the dice are ejected freely upon a table as in an ordinary way and seemingly in 40 a haphazard manner and yet wherein the result of the throw, namely the two top numbers visible to the player or manual operator, is in accord with mechanical actions of the machine desired as a result of such a throw.

I employ for this purpose as many sets of dice as are needed to represent the various combinations of throws and arrange these in compartments in a positive manner as desired and for a full description of the machine further reference may be had to the drawings, in which;

Fig. 1 is a plan view of the assembled machine.

Fig. 2 is a larger plan view with the top removed.

Fig. 3 is a vertical section thru the center of the 55 machine.

Fig. 4 shows the hand for returning a pair of dice to its compartment in a plan view.

Fig. 5 shows a segment of the wheel containing the compartments of the dice.

Fig. 6 is an elevation showing the path of the wheel rotatably mounted on its crank which in turn rotates one-half a revolution during the operation. This is to more clearly show the functions of various associated parts.

Figs. 7, 8 and 9 are detailed views of the indicator and its associated parts.

Fig. 10 is a sectional elevation thru the main shaft showing the flange used to actuate certain levers and parts.

Fig. 11 is a plan view just beneath the cover 15 showing a detail of the ejector lever and its assembly.

Fig. 12 is a sectional elevation thru the dice table and its transparent cover.

Fig. 13 shows a sectional elevation thru the 20 main shaft looking towards the operating handle.

Referring more particularly to said drawings, in which like numerals of reference indicate like parts throughout, 1 indicates a cover for main box enclosure which has four sides 2 and a bottom 3. The cover has a large opening 4 situated above the dice table 5. Another opening 6 (referring to Fig. 1) lies above an indicator 7 and a slot 8 is provided for the insertion of a coin for 25 operation.

A handle 9 is employed to actuate the machine and turns one-half revolution in so doing. Referring to Figs. 2 and 3 the handle 9 is rotatably mounted in one of the sides 2 and has rigidly fastened to itself a cast member 10. A coin-operated 30 lever 11 is adapted to lock and unlock said member 10 by the insertion of a coin in the machine, and opposite thereto is a connecting rod 12 connecting the crank lever 13 for rotation of the vertical shaft 14. A lever 15 portraying a human 40 hand is fastened to said shaft 14 to slide the dice from the table 5.

A projecting lug 16 on the cast member 10 bears against a pin 17 (see also Fig. 13) pressed thru the main shaft 18 for rotation thereof said 45 shaft 18 being rotatably centered within a hole in the handle 9. At the end of the projecting lug 16 is a screw stud 19 threading a pawl 20 adapted to engage two grooves 21 cut into the hub of the flange member 22, said flange being freely mounted on the main shaft 18. A spring 23 is employed between said flange member 22 and said pin 17 of sufficient strength to slide said flange member 50 along said shaft.

A pin 24 is riveted outwardly onto said flange 55

and is adapted to engage first a main push lever 25 employed to deliver the bottom vended article 26 from its stack thru a suitable opening into the exterior cup 27. Secondly said pin 24 is 5 adapted to either engage or not engage the coupon or prize lever 28 likewise employed to deliver a bottom prize article 29 from its stack into said cup 27. The main lever 25 is guided in a stud post 29' attached to the bottom (see Fig. 10) and 10 the lever 28 is held by the fulcrum 30 rotatably supported by the L-shaped member 31. At the lower end of the fulcrum 30 is the lever 32 which 15 is the one that pushes the prize from its container. Springs not shown are employed for returning said levers to their original positions after movement by said pin.

Integral with said flange member 22 is an eccentric cam which actuates the ring 33 to an upper and lower position. Adjacent thereto a bearing post 34 attached to the bottom of the machine is used to support the main shaft 18 which is firmly connected to the crank 35 which holds at its outer end the crank sleeve 36.

Before the insertion of the coin the crank is 25 down 180 degrees from the position shown. Rotatably mounted on the crank sleeve 36 is a bushing sleeve 37 pressed into the compartment wheel 38. Many teeth 39 are cut into the projecting end of the bushing 37 (see also Fig. 6) and engage 30 in its bottom position a ratchet member 40 rotatably secured to the bearing post 34 and held in engaging position by a spring member 41 bearing upon its top side.

A brake shoe 42 is flexibly held by a flat spring 35 43 which is screwed to the back side 2 of the box and the spring 43 is arranged to engage said shoe forcibly with the wheel 38 when the crank is radially disposed toward said shoe in its travel. Firmly attached to the wheel 38 is a toothed wheel 40 44 whose teeth correspond in number and position with the compartments 45 cast integral into the outer rim of the wheel 38.

A guide plate 46, extending from top to bottom of the box and attached thereto, holds at its 45 upper portion the mouth 47 of the dice table 5, said mouth being disposed exactly opposite the final stopping place of any compartment after rotation and locking. The compartments are brought and locked into said final stopping position by the lip of the spring member 48 engaging the teeth of the wheel 44 at the final travel of the crank. The spring member 48 is riveted to said 50 guide plate 46, which also serves the purpose of keeping the dice within their compartments as desired.

Threading thru the crank sleeve 36 is the shaft 49 whose end nearest the crank holds a spring 50 and a washer 51 riveted thereto at its end. Its other end is firmly riveted to the indicator wheel 60 7 but the shaft continues at a smaller diameter to support the rotating roller 52 held in place by the collar 53 and cotter pin 54. A round pointed stud member 55 is riveted to said wheel 7 so as to coincide upon rotation with a matched hole 56 drilled into the hub of the wheel 38 to permit its entry therein if in proper position therefor.

A cast substantially L-shaped arm 57 is pivoted to the base by the brackets 58 and supports at its upper end a pointed pin 59 whose point coincides 70 with the axis of the main shaft 18 upon extension thereto. Held by the pin 59 (see also Figs. 7, 8 and 9) and a further pin 60 is a disc 61 with a portion cut away at its top to allow the passage therethrough of the roller 52. One side of said 75 opening (see Fig. 9) is cut at an angle for thrust-

ing engagement to an outer position upon engagement therewith by said roller. Holes 62 are drilled into the indicator wheel 7 at a radius equal the crank radius and coincide with in number and position the compartments in the wheel 48 when the pin or stud 55 lies in the hole 56 and upon the locking of the wheel with such engagement a hole 62 lies exactly opposite the point of the pin 59 for entry therein. The lower extended member of the L-shaped arm 57 is connected by a rod 63 to the eccentric cam ring 33 for movement there- 5 with.

An ejector rod 64 is rotatably adapted to enter a bevelled hole cast behind each compartment of the wheel 38 and forcibly eject a pair of dice 15 therefrom. Referring to Fig. 11 the rod 64 is secured to the member 65 which is rotatably mounted on the stud 66 which is screwed to the top underneath. A lug integral with said top and shown in section supports a pointed pin 67 20 actuated by a spring 68 both of which lie within a drilled hole and the pin bears into slots cut into the flange of the member 65. It serves to partially lock said flange from rotation. A flat lever 69 is connected to the hand lever 15 thru 25 a stud 70 and is used to actuate the ejector rod 64 as follows. A pin 71 which secures the rod 64 extends below and a slot 72 in the lever 69 is guided thereby. Two springs 73 are attached to the lever 69 by studs 74 and their other ends 30 thread small lugs cast onto the member 65. Their tension is almost sufficient at maximum to release the flange from the pin 67 and upon the slot positively striking the pin 71 and disengaging pin 67 from its notch the ejector rod 64 35 snaps forward or backwards as the case may be.

Referring to Fig. 4 the dice table 5 is provided with two guiding strips 75 and 76, the latter disposed as an arc with its center at the axis of the shaft 14. Referring to Fig. 13 a spring member 77 is screwed to the side 2 just beneath the lip of the coin lever 11. Above the dice table and fastened to the top is a transparent cover 78. An extension of the arm on member 57 carries a wire member 79 attached at its upper end 45 to the coin lever 11 thru a slotted hole (see Fig. 13).

In operation a coin is inserted in the slot 8 and after being tested by various means old in the art (and not shown) it falls on the lever 11 50 and raises it slightly from engagement with the notch in member 10 which is 180 degrees from the positions shown. This permits the handle 9 to be rotated counter-clockwise towards the operator thru one-half turn. Its projection 16 carries the main shaft 18 with it by bearing against the pin 17. Upon rotating, the pawl 40 engaging the teeth 39 spins the wheel in proportion to the speed given the handle at starting (see Fig. 6). Said wheel 38 is brought against the brake 60 42 as the crank rotates and stops its spinning. Near the end of the crank's travel the spring member 48 enters between the points of the teeth in the wheel 44 and thereby brings the wheel 38 and its top compartment 45 into a center position relative to the mouth 47 of the table 5.

During this operation the connecting rod 12 has rotated (thru the arm 13 and shaft 14) the arm 15 to its outer position as shown, and the arm 15 has by the lever 69 brought tension on 70 the ejector rod 64 to snap it forward. The ejector passes thru the opening at the rear of the dice compartment and throws the dice therein out upon the table 5. Two guide strips 75 and 76 prevent their leaving the table and the trans- 75

parent cover 78 is so spaced above the table (see Fig. 12) that the dice may spin or wobble but cannot turn over since the cover's height above the table is less than a diagonal thru the dice itself. The same effect may be obtained by causing such movement of the dice in the compartments in which they are carried without ejecting them onto a table. The compartment 45 is likewise a rather confined space for the dice so that the dice once placed in the compartment with two desired numbers on top may never be able to turn over and thereby change its reading when viewed from above.

The indicator wheel 7 has printed upon its outer rim numbers or symbols which correspond with the setting of the dice in their respective compartments and these coincide when the stud pin 55 lies in the matched hole 56 drilled in the hub of the wheel 38. It is in such a position at the start when the coin is inserted, and therefore indicates thru the opening 6 in the top (which lies just forward of the ejector rod 64) a number corresponding with the throw of the dice onto the table which operation has just been described above.

During this time the flange member 22 has not moved since the pawl 20 is designed to rotate it only upon the reverse motion of the handle by the operator (or a spring suitably used for such purpose). The pin 24 at this moment is 180 degrees from the positions shown in the drawings and upon the return of the handle it engages the lever 25 to push the vended article 26 from beneath its stack into the cup 27, and at the same time the eccentric ring 33 has moved to its downward position rotating slightly the arm 57. This arm 57 pulls wire member 79 to prevent the coin lever locking the member 10 so that the handle may be operated once more without the insertion of a coin. Simultaneously the arm 57 has brought the pin 59 towards the wheel 38 and the pin 59 enters a hole 62 in the indicator wheel 7 (as shown in Fig. 7).

During the return of the handle 9 the main shaft 18 has not turned and the wheel 38 is still held by the ejector rod 64 and the spring arm 48, however the arm 15 has been rotated by the rod 12 and returns the dice into their empty compartment and at the end of said movement of arm 15 the ejector rod 64 is pushed by the dice and the lever 69 out of engagement with the wheel compartment. The dice are guided by the strips 75 and 76 and a thumb projecting on the hand 15 is used to prevent their jamming by forcing one ahead of the other at the mouth 47. This action is completed just prior to the handle's complete return, the wire connecting rod 12 flexing slightly under the continued movement of the handle. The projection 16 on member 10 strikes the pin 17 and since the ejector rod 64 is out of the way the crank assembly returns by gravity or a suitable spring to its bottom position again.

As the crank 35 starts downward from its top to bottom center position with the ejector rod 64 out of the way, the spring member 48, still engaging the bottom slot of a tooth on the wheel 44, travels with said wheel 44 for a short distance approximately equal to the distances between adjacent compartments in the wheel 38. This engagement keeps the wheel 38 from rotating so that said wheel moves merely in practically horizontal travel at the top of the arc. Simultaneously the crank sleeve 36 holding the shaft 49 moves the indicator wheel 7 which must rotate

about the center of the pin 59 whose center lies in the axis of the main shaft 18. For any angular movement of the crank sleeve 36 the indicator wheel 7 must likewise rotate the same angle relative to the true vertical.

This gives an angular movement between the wheel 38 and the indicator wheel 7 at the beginning of travel and this angular travel equals the rotative travel of the crank 35. This travel forces the tapered pin 55 from its socket within the hole 56 at the start of travel and so positions the roller 52 (see Figs. 7, 8 and 9) outwardly from the wheel 38 that it strikes against the angular lip cut into the disc 61 and upon further travel causes it to move even further outwardly as shown by dotted lines in Fig. 9. In this position which it retains during the continued downward and return stroke of the crank 35, the pin 55 is out of engagement with the wheel 38 and the spring 50 (held by washer 51) is in its maximum compressed position. The spring 50 is materially stronger than the spring 23 whose function is merely to slide the flange member 22 along the main shaft 18 which it does upon the said compression of the spring 50 as described above. Likewise in this position of the flange member 22 the pin 24 is inwardly disposed relative to the lever 28 and unable to engage same.

Upon the return of the handle 9 a new spinning is imparted to the wheel 38 similar to that described on the initial stroke and said wheel 38 again reaches top center and a locked position through the engagement of the spring member 48 and by chance it may have stopped with the same compartment uppermost as upon the initial operation of the handle 9 or, as most likely has happened, it will present a different compartment with its resultant throw of the dice upon the table. Should the throw be identical with the original throw then by necessity the pin 55 would coincide with the hole 56 and, upon the roller 52 reaching the opening in the disc 61, the shaft 49 with its assembly would move inwardly to the depth of the hole 56. In this position the shaft 49 impels through its spring 50 and washer 51 the flange member 22 along the shaft 18 and positively places the pin 24 into engaging position with the lever 28 as seen in Fig. 10 which it actuates to deliver a prize upon the return stroke of the handle 9 in its final operation.

During the second stroke of the handle 9 the indicated throw of the dice (shown as a six in Figs. 1 and 2) disappears below the opening 6 through the rotation and downward movement of the indicator wheel 7 but of necessity returns at the uppermost travel of the crank 35 to the original indication, namely a six. This is due to the continued engagement during such time of the pin 59 within the hole 62 to return the indicated six back to its uppermost position beneath said hole 6. Upon the last stroke of the handle 9 the flange member 22 in rotating 180 degrees actuates through its eccentric cam and ring 33 the L-shaped member 57 to bring the pin 59 and disc 61 out of engagement with the indicator wheel 7.

Should, however, the second throw of the dice be other than the original throw, then the pin 55 would not coincide with the hole 56 in the wheel 38 and the shaft 49 could not move inwardly of sufficient distance to actuate the flange member 22 (as described above) so that the pin 24 might thereby engage the lever 28 for delivering a prize. As a result no prize is given upon the final stroke of the handle 9.

It is essential however, upon the final stroke of said handle, that the indicator wheel 7 be brought into coinciding position with the wheel 38 by the pin 55 resting in its hole 56 as this is its starting position upon the insertion of a coin for a new vending operation. Referring to Fig. 8, this is accomplished in the following manner. The pin 59 in its outward position as shown (upon the final stroke of the handle 9) is still adapted to engage the hole 62 slightly since the pin 55 does not lie within its socket or hole 56 and upon the downward travel of the crank 35 a rotary motion is imparted to the wheel 38 by its striking the brake shoe 42 and in an opposite direction to the rotation of the indicator wheel 7 and the crank 35. This rotation between the wheel 38 and the indicator wheel 7 will eventually bring the pin 55 to coincide with its associated hole 56 and the spring 59 will immediately act to engage said pin into said hole forcefully and simultaneously result in the release of the pin 59 from engagement with the hole 62 through this inward movement of the indicator wheel assembly. In this final position the indicator wheel 7 is free to rotate with the dice wheel 38 and coincides with it relative to the indication printed on the outer rim of the indicator and the throw of the dice as positively arranged in their respective compartments.

30 To permit the second throw of the dice without the insertion of another coin, the rod 79 attached to the arm 57 pulls the coin lever 11 (see Fig. 13) downward during this second throw to prevent its locking engagement with member 10 in the notch (shown 180 degrees from said latching position). The spring member 77 serves the purpose of preventing the dropping of the coin until the member 10 has been rotated during which action the raised lip on member 10 further rotates the coin lever 11 to permit the release of the coin.

Many variations could be employed in my invention such as having the opening 4 in the top immediately over the compartments 45 with suitable openings therein so that the dice may be viewed therein without ejection therefrom. Also pins could be placed on the wheel 44 to actuate various mechanisms upon the arrival of certain lucky numbers and such variations would lie 50 within the scope of my invention which I have shown in its preferred form only.

What I claim is:

1. In a dice game device, a plurality of sets of dice positively arranged to represent the various combinations capable of being thrown, compartments capable of holding each set of dice as arranged, means for bringing singly and by chance a set of dice to the view of the player, and means for confining the dice when brought into view within a space the depth of which is greater than the perpendicular but less than the diagonal dimension of the dice, whereby the dice may be caused to spin and wobble thereby simulating, in effect upon the eye, the normal action of dice when thrown.
2. In a dice game device, a plurality of sets of dice positively arranged to represent the various combinations capable of being thrown, compartments capable of holding each set of dice as arranged, means for bringing by chance a compartment into a locked position and means for ejecting the dice from said compartment onto a table and beneath a transparent cover.
3. In a dice game device, a plurality of sets of dice positively arranged to represent the various

combinations capable of being thrown, a wheel containing compartments capable of holding each set of dice as arranged, means for spinning and locking said wheel, and means for bringing in its locked position a set of dice to the view of the player.

4. In a dice game device, a wheel containing compartments capable of holding each a set of dice positively arranged in various combinations and capable of being spun and locked, an indicator with numerals or symbols in accord with said arrangement of combinations adapted to register the result of a spin of said wheel.

5. In a dice game device, a wheel containing compartments capable of holding each a set of dice positively arranged in various combinations and capable of being spun and locked, an indicator with numerals in accord with said arrangement of combinations adapted to register the throw of a set of dice, and means for holding said registration during a subsequent throw of the dice.

6. In a dice game device, a wheel containing compartments capable of holding each a set of dice positively arranged in various combinations and capable of being spun and locked, means for registering the throw of a set of dice from its compartment, means for holding said registration during a subsequent throw, and means for releasing said registration by the repetition of the original throw.

7. In a dice game device, a wheel containing compartments, a set of dice arranged in each compartment and incapable of turning over, a table upon which the dice are ejected, and a transparent cover so arranged above said table as to permit the free ejection of said dice without permitting their turning over.

8. In a dice game device, a wheel containing compartments capable of holding each a set of dice positively arranged in various combinations, means for spinning and locking said wheel in a set position relative to the spacing of said compartments, and means for confining the dice when brought into view within a space the depth of which is greater than the perpendicular but less than the diagonal dimension of the dice, whereby the dice may be caused to spin and wobble thereby simulating, in effect upon the eye, the normal action of dice when thrown.

9. In a dice game device, a plurality of sets of dice definitely arranged to represent various combinations, said dice being normally hidden from view, means to expose by chance one of said sets of dice to view while maintaining the definite arrangement of said sets of dice, said dice being movable, and means for confining the dice when exposed to view by said last-mentioned means so that they cannot be turned over but may be moved to simulate a random or uncontrolled action as if thrown by hand.

10. In a dice game device, a container having a plurality of compartments, a plurality of sets of dice located in said compartments, said dice being definitely arranged to represent various combinations, a table located in proximity to said container, means to throw by chance one of the sets of dice upon said table, and means to return said set of dice to its compartment in the container while maintaining the definite arrangement of said sets of dice.

11. In a dice game device, a container having a plurality of compartments, a plurality of sets of dice located in said compartments, said dice being definitely arranged to represent various combinations, a table located in proximity to

5 said container, means to project by chance one of the sets of dice upon said table, means to return said set of dice to its compartment in the container while maintaining the definite arrangement of said sets of dice, and an indicator operatively connected to said container to register said throw of the dice.

10 12. In a dice game device, a container having a plurality of compartments, a plurality of sets of dice located in said compartments, said dice being definitely arranged to represent various combinations, a table located in proximity to said container, means to project by chance one of the sets of dice upon said table, means to return 15 15 said set of dice to its compartment in the container while maintaining the definite arrangement of said sets of dice, an indicator operatively connected to said container to register said throw of the dice, and means to maintain said registration of the indicator during subsequent throws 20 20 of the dice until a predetermined combination is thrown.

25 13. In a dice game device, a rotatable wheel having a plurality of compartments adjacent its periphery, a plurality of sets of dice located in said compartments and definitely arranged to represent various combinations, a table located in proximity to the periphery of said wheel, means to rotate said wheel to bring by chance a compartment into communication with the surface of said table, means to eject a set of dice from said compartment onto said table, and means to return said set of dice to its compartment in the wheel while maintaining the definite arrangement 30 35 of said sets of dice.

40 14. In a dice game device, a rotatable wheel having a plurality of compartments adjacent its periphery, a plurality of sets of dice located in said compartments and definitely arranged to represent various combinations, a table located in proximity to the periphery of said wheel, means to rotate said wheel to bring by chance a compartment into communication with the surface of said table, means to eject a set of dice from said compartment onto said table, means to return said set of dice to its compartment in the wheel while maintaining the definite arrangement of said sets of dice, and an indicator operatively connected to said wheel to register the combination thrown upon the table.

45 15. In a dice game device, a container having a plurality of compartments, a plurality of sets of dice located in said compartments and definitely arranged to represent various combinations, said dice being normally hidden from view, means to expose to view by chance one of said sets of dice, and means operated by the expo-

sure of certain dice combinations to vend an article of merchandise.

5 16. In a dice game device, a container having a plurality of compartments, a plurality of sets of dice located in said compartments, said dice being definitely arranged to represent various combinations, a table located in proximity to said container, means to throw by chance one of the sets of dice upon said table, means to return said set of dice to its compartment in the container while maintaining the definite arrangement of said sets of dice, and means operated by the throwing of certain dice combinations upon the table to vend an article of merchandise.

10 17. In a dice game device, a plurality of dice 15 definitely arranged to represent various combinations, said dice being normally hidden from view, means to expose by chance a predetermined number of said dice to view while maintaining the definite arrangement of said dice, said dice 20 being movable, and means for confining the dice when exposed to view by said last-mentioned means so that they cannot be turned over but may be moved to simulate a random or uncontrolled action as if thrown by hand.

25 18. In a game device, a plurality of movable objects having indicia thereon and being arranged to represent various combinations, said objects being normally hidden from view, means to expose by chance certain of said objects to view while maintaining the definite arrangement of all said objects, said objects being movable, and means for confining the objects when exposed to view by said last-mentioned means so that they cannot be turned over but may be moved 30 35 to simulate a random or uncontrolled action as if thrown by hand.

40 19. In a game device, a plurality of movable objects positively arranged to represent various combinations, compartments capable of holding 40 a predetermined number of said objects as arranged, means for bringing by chance a predetermined number of said objects to the view of the player, said objects being movable, and means for confining said objects within a space in which 45 they cannot be turned over but may be moved when brought into view to simulate a random or uncontrolled action as if thrown by hand.

45 20. In a game device, means for supporting a plurality of movable objects normally hidden from view, means for moving the objects into the view of the player, and means for confining said objects when so exposed to view within a space in which they cannot be turned over but may have sufficient freedom of movement to give the 50 55 effect upon the eye of a turning action.

BLANCHARD D. SMITH.
